UNITED STATES PATENT OFFICE.

ERIC P. MUNTZ, OF BUFFALO, NEW YORK.

FOUNDATION FOR RAILWAY SCALES.

Application filed March 25, 1926. Serial No. 97,254.

This invention relates to a foundation for use in connection with a railway scale.

The pits forming the main part of railway scales, as heretofore constructed, are very costly on account of the steel beams and other metal structural parts employed, the excessive amount of excavation required and the undue quantities of concrete entering into the building of the foundation.

It is the object of this invention to provide a foundation for railway scales having a pit which dispenses with the use of expensive steel beams or parts, and which reduces the excavation and the amount of concrete employed to a minimum, but furnishes the requisite strength and facility for assembling and dismembering the parts of the scale.

In the accompanying drawings:

Figure 1 is a top plan view of railway scale foundation constructed in accordance with my invention.

Figure 2 is a vertical longitudinal section of the same.

Figures 3, 4 and 5 are vertical transverse sections, on an enlarged scale, taken on the correspondingly numbered lines in Fig. 1.

Figure 6 is a fragmentary vertical transverse section on an enlarged scale, taken on line 6—6 Fig. 1.

Figure 7 is a top plan view of the same.

Figure 8 is a fragmentary vertical section, on an enlarged scale, taken on line 8—8 Fig. 1.

Similar characters of reference indicate like parts in the several figures of the drawings:

In railway scales it is customary to support the cars and their contents or load which are to be weighed upon a track section composed of two vertically movable live rails 11, 11, while the locomotive or other cars coupled with the active cars but not to be weighed are run upon a track composed of two dead rails 10, 10 which are immovable and arranged adjacent to the live rails, and in addition two sets of immovable approach rails 13, 13—14, 14, are provided over which the cars and locomotives are run on and off the live and dead scale rails, respectively.

The live and dead rails are mounted on the pit arranged within an excavation for the scale, which pit embodies my invention.

and in its preferred form is constructed as follows:

The numeral 15 represents the footing or bottom of the pit, 16 the deck, roof or top thereof, 17, the longitudinal or side walls of the same and 18 its transverse or end walls. 60 Each of these members is constructed of reinforced concrete, the concrete 19 of the several pit members is united into one common integral mass, and the reinforcement 20 embedded in adjacent pit members overlaps. 65 A pit of box like form is thus produced which is very strong and durable, and capable of sustaining the maximum weight which may be imposed on the same and still permit of making the pit members of less 70 thickness than has been customary heretofore. As a result the amount of concrete in the pit is materially reduced and less excavation is required thereby effecting a considerable saving in the cost of building the 75 foundation.

A reinforced box like pit made of one mass of reinforced concrete permits of dispensing with the usual steel beams for supporting the deck of the pit and thereby effects a considerable saving in cost of construction. 80

The dead rails 10, 10 may be mounted on the upper surface of the deck in any suitable manner so as to form an uninterrupted continuation of the approach rails 14, 14 leading to and from the same. As shown in Figs. 1, 5 and 8, the dead rails are supported by ties or sleepers 21 and held in place on the deck by means of clips 22 engaging with 85 the base of this rail and fastening bolts 23 passing through the deck, sleeper and clips, as shown in Fig. 8. The sleepers of the two dead rails are also held in position transversely relatively to each other by cross tie 90 rods 24 embedded in the upper part of the deck.

The live rails of the scale are mounted over the deck of the pit and capable of moving vertically relatively to the companion 100 approach rails 13, 13 which latter are immovably mounted on opposite ends of the deck so as to form interrupted continuations of the same. Each of the live rails is secured to the upper end of a plurality of 105 posts 25 which project upwardly through a longitudinal row of openings 26 in the deck. The lower ends of the corresponding pairs

of posts of both live rails are connected by cross beams 27 and the several cross beams are connected in groups at their opposite ends by longitudinal beams 28.

5 The longitudinal beams are supported on the longitudinal levers 29 of the scale which are pivotally mounted on the footing or bottom of the pit and from these longitudinal levers motion is transmitted by a transverse lever 30 to the scale beam in the scale house 31 in any well known and approved manner.

10 For the purpose of preventing rain, snow and dirt from passing through the holes 26 into the pit weather guards 32 are provided which are mounted on the top of the deck and overhang opposite sides of the post openings 26 and adjacent base portions of the live rails, as shown in Figs. 1, 3, 6 and 7.

15 In order to reliably support the approach rails in position relative to the live and dead scale rails foundation extensions are provided on opposite ends of the pit each of which consists of a transverse pier 33 of reinforced concrete of L-form in section which 20 is set into the ground, and two reinforced concrete extension beams 34 arranged lengthwise and united at their outer and inner ends with the respective pier and end wall of the pit, as shown in Figs. 1 and 2. By 25 this means the foundation for the scale as a whole is strengthened and less concrete and a correspondingly reduced amount of excavation is required thereby economizing in the cost of installation.

30 35 The upper part of one or the other, and preferably both end walls of the pit are provided with openings 35 through which the metal parts of the scale, particularly the longitudinal and transverse girders or beams 40 and levers may be passed in erecting the internal scale parts or when taking the same down for repairs or other purposes. To permit of thus utilizing the openings 35 in the end walls of the pit the extension concrete beams 34 are so spaced that together 45 the same are narrower than the pit and permit of locating the openings 35 in the pit and walls outside of the extension beams so as to enable the scale parts to be freely 50 passed through these openings into and out of the pit.

55 By providing the pit with the openings 35 it is possible to build the pit complete and mount the dead rails thereon before beginning the erection of any part of the scale within the pit. It is also possible to make 60 repairs to scale and remove parts of the same from the pit and restore the same through the openings without interfering with traffic over the dead rails as would be the case if the deck had to be taken down in order to make the scale parts within the pit accessible for repairs and replacement in the manner heretofore known. This improved 65 form of pit therefore is particularly well

suited for use on a track which serves a plurality of customers on a railway line inasmuch as the car service to other customers is not interrupted while making repairs on the respective scale.

70 After the scale is installed in the pit the openings 35 may be closed by a closure of any suitable character which can be readily removed when access to the interior through these openings is necessary.

75 This closure is preferably constructed of brick as shown at 36 in Fig. 4.

80 Aside from eliminating structural steel or timber, girders or beams or other kind of separately placed parts to support the dead rail deck or roof this organization has the further advantage of reducing the quantities of excavation and concrete to a minimum.

85 Moreover this pit forms practically a square box of reinforced concrete which is capable of resisting strains in all directions without making the same unduly heavy, it also provides adequate anchorage in poor soil conditions so that piling and expensive ground preparations for the foundation are rendered unnecessary.

90 Furthermore this construction forms a pit which is practically waterproof and it also provides means for moving any member of the scale mechanism into and out of the pit with ease and facility without disturbing any part of the pit or deck, thereby avoiding the expense of constructing an off-set pit for this purpose as has been necessary heretofore.

95 Advantages inherent in this construction in addition to those already mentioned are as follows:

100 A pit is provided in which the bottom, top and walls can be made by pouring cement around the reinforcement by one continuous operation and thereby produce a seamless enclosure which is waterproof and capable of being produced at comparatively low cost.

105 It provides an extended and uniform bearing surface which permits of economical construction in soft soil without the use of piles or spread footings.

110 It provides for construction in a cofferdam of minimum width using the cofferdam as the exterior form for the concrete, saving cost of outside forms and reducing size of cofferdam necessary.

115 All perishable deck materials are eliminated so that repairs of the same are not required. Less excavation and concrete are required owing to a reduction in thickness of the bottom and walls, this being possible 120 due to the box like form of the pit which is made of reinforced concrete, and therefore much stronger than a pit in which the deck is made separate from the walls.

125 A uniform and connected bearing is pro-

vided by the bottom for the several scale stands, thereby eliminating heavy concentrated soil pressures under isolated piers for the scale stands, as has been the practice 5 heretofore.

An economical deck is provided which can be readily protected against the majority of industrial chemicals and thereby gives the greatest protection to the scale mechanism.

10 A pit is provided which when subject to water conditions can be finished, painted, heated and kept to serve as a proper housing which the scale mechanism requires.

15 I claim as my invention:

1. A scale foundation comprising a pit having a deck, upright walls, and a footing, said deck, walls and footing being constructed of an integral mass of reinforced concrete

and said deck having an upper surface for 20 supporting dead rails and a plurality of openings adapted to receive posts which support live rails above the deck from the scale mechanism below the deck.

2. A scale foundation comprising a pit 25 having a deck, upright walls, and a footing, said deck, walls and footing being constructed of an integral mass of reinforced concrete and said deck having an upper surface for supporting dead rails and a plurality of 30 openings adapted to receive posts which support live rails above the deck from the scale mechanism below the deck and said walls being provided with openings for the passage of scale parts into and out of the pit. 35

In testimony whereof I hereby affix my signature.

ERIC P. MUNTZ.
